MOTION PICTURE FILM SPLICER

Leonard Dickstein, 206 W. 22nd St., Deer Park, N.Y.
11729, and Barry Green, 732 De Mott Court, West-
bury, N.Y. 11590

Filed Dec. 8, 1969, Ser. No. 20,407

Term of patent 14 years

Int. Cl. D16—07

U.S. Cl. D61—1

FIG. 1

FIG. 6

FIG. 2

FIG. 3

FIG. 4

FIG. 5

FIG. 7

FIG. 8

FIG. 9

FIG. 10

FIG. 1 is a top plan view of a motion picture film splicer showing our new design;

FIG. 2 is an end view;

FIG. 3 is a left side view;

FIG. 4 is a right side view;

FIG. 5 is a bottom view;

FIG. 6 is a top plan view of another embodiment of the FIG. 1 splicer, wherein the arrangement of pins, ridges, and slots in the upper surface of the splicer is modified;

FIG. 7 is an end view;

FIG. 8 is a left side view;

FIG. 9 is a right side view; and

FIG. 10 is a bottom view.

We claim:

The ornamental design for a motion picture film splicer, substantially as shown and described.
